[57] **CLAIM**

The ornamental design for a nasal insert for absorbing mucus and the like, as shown and described.

DESCRIPTION

FIG. 1 is a perspective view of a nasal insert for absorbing mucus and the like, showing my new design;

FIG. 2 is a top plan view thereof;

FIG. 3 is a side elevational view thereof;

FIG. 4 is an end elevational view thereof;

FIG. 5 is a bottom plan view thereof.

Opposite side of FIGS. 3 and 4 are identical to that shown in FIGS. 3 and 4.

FIG. 1

FIG. 2

FIG. 3

FIG. 4

FIG. 5
